UNITED STATES PATENT OFFICE.

CHARLES O. ROGERS, OF ATLANTIC, MASSACHUSETTS, ASSIGNEE TO CHARLES J. JAGER COMPANY, OF BOSTON, MASSACHUSETTS, A CORPORATION OF MASSACHUSETTS.

PORTABLE POWER WOOD-SAWING APPARATUS.

Application filed March 2, 1922. Serial No. 540,586.

This invention relates to a portable power driven wood sawing apparatus.

The object of the invention is to provide an apparatus of this type which may readily be hauled about from place to place, operated and controlled by one man.

The object of the invention is further to provide an apparatus of this type in which an ordinary form of hydrocarbon combustion engine is employed and in which the shaft of the engine is directly connected to the shaft of the saw so that there are no losses of power through the slipping of belts or other power transmitting devices or through misalignment.

The object of the invention is further to provide an apparatus of this type in which the engine and saw shaft extend longitudinally and centrally of the supporting frame and all the parts of the apparatus are arranged symmetrically or in substantially balanced relation with respect to the longitudinal central axis so that there is a minimum of vibration, and a balanced structure is produced giving the most effective results in operation.

The object of the invention is further to produce an apparatus of this type which is compact in form, light in weight and so conveniently mounted on its wheels that it is possible for one man under favorable conditions to move it about from place to place.

The object of the invention is further to provide an apparatus of this type which requires a relatively small amount of power for its operation and which will run without the necessity of the supporting frame being in a level position.

The object of the invention is further to provide an apparatus of this type in which one set of wheels is carried by a bolster pivoted to the supporting frame on a central vertical axis to permit the steering of the apparatus and in which means are provided to lock the bolster to the frame to prevent a relatively transverse tilting movement and thus position the supporting frame firmly for the sawing operation.

These and other objects and features of the invention will appear more fully from the accompanying description and drawings and will be particularly pointed out in the claim.

In the drawings Fig. 1 is a top view of an apparatus embodying a preferred form of

the invention, the draft tongue being shown partially broken away.

Fig. 2 is a front elevation partially broken away and partially in vertical cross section showing the front end of the frame, the steering bolster, wheels and draft tongue;

Fig. 3 is a detail in vertical cross section taken on the line 3-3 of Fig. 1 with the bolster shown in locked position and the draft tongue shown in dotted lines in draft position;

Fig. 4 is a side elevation of the main and rear portion of the apparatus shown in Fig. 1;

Fig. 5 is a view in vertical cross section taken on the line 5-5 of Fig. 1 showing the tilting wood supporting table.

The apparatus comprises a supporting frame or chassis. This supporting frame is shown as comprising a pair of longitudinal iron or steel channel beams, 1 and 2 rigidly connected by transversely extending bearing blocks, angle irons, and plates which are utilized in supporting the various parts of the apparatus.

This supporting frame is mounted upon and carried by two sets of wheels. The rear wheels 3 are carried on an axle 4 mounted in hangers 5 secured to the bottom of the beams 1 and 2.

The front wheels 6 are carried on an axle 7 and in turn carried by a bolster 8, pivoted on a central vertical axis by the bolt or king pin 9 to a hanger 10 secured to the beams 1 and 2 at the front end. The front wheels are turned about the bolt 9 to permit the steering of the apparatus and the apparatus is drawn by means of a steering bifurcated draft tongue 11. In the form shown this tongue is shown as an iron rod bent into loop form with its ends bent about the axle 7 so as to pivot thereon.

It is very desirable that when the apparatus is set up in position for the sawing operation the supporting frames shall be rigidly and firmly positioned. The invention provides a means for locking the front bolster to the frame to prevent any relative transverse tilting movement between the frame and the front bolster with its wheels. A simple and effective means for securing this result is illustrated as embodying one form of this feature of the invention. A plate 12 extends transversely of and is secured to the top of the beams 1 and 2 at the

front end of the frame above the axle 7. This plate 12 is provided at its outer ends with apertures. Rods 13 extend down through these apertures and are provided at their lower ends with hooks 14 adapted to embrace the axle 7. At their upper ends the rods 13 are threaded at 15 and provided with wing nuts 16 seating on the plate 12. When the apparatus is being moved the rods 13 are unhooked and preferably drawn up out of the way of the axle. When the apparatus is located in position, the rods are hooked onto the axle and the wing nuts tightened up. The rods thus together with the bolt or king pin 9, lock the front wheels in rigid position relatively to the frame and thus secure a firm and rigid support to the frame. The front wheels may thus be locked to the frame in rigid position even if the front axle is tilted somewhat with respect to the frame due to unevenness in the ground.

The motive power is furnished by a hydrocarbon combustion engine of any suitable compact type. This engine is shown as having its bed plate 17 bolted at 18 to plates 19 secured to the top of and extending transversely of the beams 1 and 2 with the engine shaft 20 extending centrally and longitudinally of the frame. It will be seen that the center of gravity of the entire engine 21 is disposed by this mounting somewhat to one side, in this case to the left side, of the frame. The small fly wheel 22 which usually forms a part of one of these engines may be left on the shaft and is so illustrated.

The saw shaft 23 extends centrally and longitudinally of the frame in line with the engine shaft 20 and is directly and rigidly connected thereto so that in effect the shafts 20 and 23 act as a single rigid shaft. This saw shaft 23 is journaled in bearings 24 formed in bearing blocks 25 extending transversely of and secured to the beams 1 and 2. At its rear end, the shaft 23 carries the circular saw 26 which preferably is positioned beyond the rear end of the supporting frame and may thus have the necessary clearance without requiring any higher mounting of the shaft with respect to the frame than is required by the position of the engine.

A heavy fly wheel 27 is mounted on the saw shaft to provide for the necessary momentum.

The wood is fed to the saw by a table extending longitudinally of the frame and mounted thereon at one side of the shaft for transverse movement between the saw and the engine. Preferably this table is mounted to tilt or pivot and thus secure the necessary transverse movement.

This table comprises a skeletonlike structure including the longitudinally extending beams 28 and 29 and the transverse plates 30 to 37 upon which the wood rests. The inner ends of the plates 32, 33, 34, and 37 are upturned to align and position the wood and the upturned ends of the plates 34 and 37 form an integral loop 38 which straddles the saw and acts as a saw guard.

The table frame is supported by arms 39 and braces 40, depending therefrom. These arms 39 at their lower ends are pivoted at 41 to angle irons 42 extending transversely of and secured to the bottom of the frame beams 1 and 2. A chain 43 limits the outward movement of the table.

After the operator has started the engine he places the wood on the table against the upturned ends of the transverse plates and then swings the table over toward the central axis of the frame, thus bringing the end of the wood against the saw; the table swinging about the pivots 41.

It will be noted that the wood sawing table is located on that side of the central shaft opposite to that at which the center of gravity of the engine is disposed, so that the wood sawing table, and the weight of the engine, substantially counterbalance. The other portions or the remainder of the entire apparatus are constructed and located symmetrically with respect to the axis of the central shaft, thus the entire apparatus is well balanced and presents a most effective construction, utilizing to the fullest extent the power developed by the engine and insuring a minimum amount of vibration.

Having thus described my invention, what I claim as new, and desire to secure by Letters Patent, is:

A portable power wood sawing apparatus comprising a supporting frame mounted on wheels, a shaft mounted in bearings on the frame and extending centrally and longitudinally thereof, a circular saw secured to one end of the shaft, a hydrocarbon combustion engine mounted on the frame at, and directly connected to, the other end of the shaft, a fly wheel secured to the shaft, a table extending longitudinally of the frame and mounted thereon at one side of the shaft for transverse movement between the saw and the engine to carry the wood to the saw, the center of gravity of the engine being disposed at the side of the shaft opposite to that at which the table is mounted and the remainder of the apparatus being transversely symmetrical with respect to the axis of the shaft.

In testimony whereof, I have signed my name to this specification.

CHARLES O. ROGERS.
